TRACTOR CABIN

Ernest Hofmann-Igl, Mitterfeld, Germany, assignor to
Firma Fritzmeier, Georg KG, Grosshelfendorf über
Munich, Germany

Filed Oct. 17, 1966, Ser. No. 4,293

Claims priority, application Germany Apr. 19, 1966

Term of patent 14 years

(Cl. D14—3)

Fig. 3

FIGURE 1 is a top, rear perspective view of a tractor cabin showing my design, a side support for the instrument panel being omitted to more clearly show the interior of the cabin;

The tractor shown in broken lines is included for illustrative purposes only.

What is claimed is:

The ornamental design for a tractor cabin, substantially as shown and described.
